UNITED STATES PATENT OFFICE.

DAVID HATHAWAY, OF GREEN ISLAND, ASSIGNOR TO FULLER, WARREN & CO., OF TROY, NEW YORK.

DESIGN FOR A COOKING-RANGE.

Specification forming part of Design No. 5,976, dated July 9, 1872.

To all whom it may concern:

Be it known that I, DAVID HATHAWAY, of Green Island, in the county of Albany and State of New York, have invented and produced a Design for Ranges, of which the following is a specification, reference being had to the accompanying photograph of a range which embodies my invention.

This design is distinguished by the following features, viz.: First, the lower section A A B, having rounded ends, with moldings c d and panel-ornaments e e, f f, all shaped and arranged together so as to appear substantially as shown in the aforesaid photograph. Second, the recessed section, composed of the central front panel G, the rear panels H H, and the side panels I J, all ornamented and arranged substantially as shown in the photograph. Third, the oven-section, consisting of the oven-doors K K having the central ornaments l l and border ornaments m m thereon, with or without the ornaments n n on the front plate, all shaped and arranged so as to appear substantially as shown in the aforesaid photographic representation. Fourth, the upper section, composed of the sliding panels P with the ornaments q thereon, substantially as shown in the photograph. Fifth, the cap-piece R, shaped and ornamented as represented in the photograph.

What I claim as my invention is—

The design for a range, substantially as shown and described.

DAVID HATHAWAY.
